UNITED STATES PATENT OFFICE.

LOUIS AUERBACH, OF NEW YORK, N. Y.

DESIGN FOR NECKWEAR FABRIC.

No. 38,947.

Specification for Design.

Patented Dec. 10, 1907.

Application filed September 18, 1907. Serial No. 393,565. Term of patent 3½ years.

To all whom it may concern:

Be it known that I, LOUIS AUERBACH, a citizen of the United States, and a resident of New York city, in the county and State of New York, have invented a new, original, and ornamental Design for Neckwear Fabric, of which the following is a specification, reference being had to the accompanying drawing, forming part thereof.

The figure is a plan view of the fabric, showing my new design.

I claim:

The ornamental design for neckwear fabric, as shown.

LOUIS AUERBACH.
